DESIGN FOR AN AMUSEMENT MACHINE CABINET TOP

Harry E. Williams and Lyndon A. Durant,
Chicago, Ill.

Application October 21, 1938, Serial No. 80,600

Term of patents 3½ years

To all whom it may concern:

Be it known that we, Harry E. Williams and Lyndon A. Durant, both citizens of the United States and both residents of Chicago, in the county of Cook and State of Illinois, have invented a new, original, and ornamental Design for an Amusement Machine Cabinet Top, of which the following is a specification, reference being had to the accompanying drawing, forming a part thereof, and in which:

Fig. 1 is a top plan view of an amusement machine cabinet top showing our new design; and

Fig. 2 is a sectional view of the same, taken on line 2—2 in Fig. 1.

We claim:

The ornamental design for an amusement machine cabinet top, as shown.

HARRY E. WILLIAMS.
LYNDON A. DURANT.
